REGULATING SYSTEM FOR GENERATOR
DRIVING ENGINES

Theodor Deeg, Berlin-Siemensstadt, Germany, assignor to Westinghouse Electric & Manufacturing Company, East Pittsburgh, Pa., a corporation of Pennsylvania

Application July 12, 1938, Serial No. 218,751
In Germany July 16, 1937

12 Claims. (Cl. 290—17)

My invention relates to electric ship propulsion systems and more particularly to a system provided with control means for securing continuous stable operation.

5 Before stating the objects of my invention some explanation of the real problems involved would be appropriate.

The torque of steam turbines is at zero speed of a turbine and rated steam admission (at rated 10 temperature and pressure) substantially equal to twice the turbine torque at rated speed. At approximately twice the rated turbine speed the torque would be equal to zero. Between these 15 three limits of turbine speed the turbine torque plotted against turbine speed follows approximately a straight line.

In ship drives, the turbine torque and its power are determined by the characteristic of the propeller power plotted against propeller speed and 20 the turbine design, (or the selection of the turbine) is, in general, so made as to correspond or fit to the maximum propeller power, namely, to fit the predetermined maximum propeller speed. Any particular ship speed, for mechanical or 25 geared drives, is in general determined by the adjustment of the steam admission, whereby, as long as a speed increase or decrease takes place (with different adjustments of steam admission) up to the rated steam admission, the speed corresponding to the characteristic of the propeller 30 power is obtained.

With turbo-electric drives of ships it is necessary to utilize a governor or rotation regulator which, by reason simply of the magnitude of the 35 rotational speed during reversing of the ship, limits the loading of the damper windings in the propeller motor. Furthermore, the (ship) reversing operation and the synchronization is simplified by the use of a rotation regulator or governor 40 because the driving machine is at all times immediately available to be interconnected and the attendant need not concern himself with the regulation of the steam admission. After completion of the synchronization the governor speed, or 45 rotation regulator, may, in a simple manner, be used to attain the desired speed. By adjustment or setting of the speed regulator or governor to the desired propeller speed the regulator automatically alters the steam admission to the generator driving machine until the selected propeller speed is secured. The governor moreover maintains this speed always constant regardless 50 of whether the power requirements rise or fall by reason of changes on the propeller resistance caused by the weather or by effects of changes in

water head. The governor has the further great advantage of maintaining the rotational speed constant when the motor and generator fall out of step and, therefore, offers an extensive reliability to the generator driving machine.

The size (or design) of the electric drive is determined by the maximum (propeller) torque occurring at full speed of the ship. Certain possible operating conditions may, however, lead to torques higher than the rated torque and must, therefore, be automatically avoided. Such cases occur, for example, in multi-screw drives when the rudder is moved hard over at full ship speed or at the loss of a propeller at full ship speed. In this case the governor will seek to increase the steam admission of the driving machine until the selected speed is again attained. At such time the danger, however, arises that the maximum permissible torque, the pull-out torque, is exceeded. This danger is eliminated in the invention because the governor for the generator driving machine has a device by reason of which the instantaneous maximum permissible torque may not be exceeded. For measuring the maximum permissible torque an electric instrument is 25 preferably used upon which the actual transmitted torque and the maximum permissible torque act in an opposite sense. The maximum permissible torque may, for example, be measured by a wattmeter instrument, the field of which is influenced by the exciting current of the generator 30 and the armature of which is influenced by the exciting current of the motor. The actual transmitted torque may be indicated by a second wattmeter instrument that is so connected to current 35 and potential transformers of the leads that it is responsive to the expression

$$\frac{E I \cos \theta}{f}$$

In this expression E represents generator voltage, f represents the frequency of the generator voltage, I represents the motor armature current, and the remaining term represents the power factor.

For limiting the maximum permissible torque, in the practical embodiment of the invention, a movable stop may, for example, be used which limits the steam admission to the driving machine. My control instrument may, of course, be designed so as to operate automatically on the governor adjustment instead of on the position of the stop limiting the opening of the steam admission valve. The instrument may also operate to

actuate the governor adjustment means indirectly.

One broad object of my invention is to maintain stable operation between a generator and a motor in a power system where the motor is large enough to take the major portion of the generator load.

Another object of my invention is to so control the operation of a prime mover driving a generator that conditions of unstable operation between the generator and a motor coupled to the generator do not arise.

A broad object of my invention in a power system embodying a generator, a prime mover for driving the generator, and a motor is to alter the speed of the prime mover as a function of the difference between the pull-out torque of the motor and the transmitted torque.

A still further object of my invention is to control the turbine speed of a turbo-electric ship propulsion drive as a function of the maximum permissible torque and the transmitted torque.

The foregoing statements of the objects of my invention are not an exhaustive recitation of objects but merely illustrative. Other objects and advantages will become more apparent from a study of the following specification and the accompanying drawings, in which:

Figure 1 is a schematic showing of an embodiment of my invention operating on the adjustment of the steam admission valve;

Fig. 2 is a schematic showing of my invention in which the control is effected by operation on the governor adjustment directly; and

Fig. 3 is a schematic fragmentary showing of my invention in which the control is effected by an indirect operation on the governor adjustment.

A regulating device of the first-named type is schematically illustrated in Figure 1. A two-gear gear-wheel pump 3, the supply amount of which varies as is known approximately proportional to the rotational speed, is driven from the turbine shaft 1 through a spur gear drive 2. For the constant outflow cross-section, as, for instance, the fixed opening 6, the supply pressure increases with the rotational speed and, therefore, in proportion to the increased supply of power. This pressure is used for rotational speed regulation. The pump supplies fluid flow through the space 4 in the opening 5 of one of the pump well shafts and through the slot or fixed opening 6 into the open. The governor adjustment may, however, be varied by adjusting the sectional area of opening 6. This is accomplished by rotation of the cam 47 to act on the sleeve 48. Further, the liquid pressure arrives through the opening 7 of the second pump well shaft in the space 8 and holds the slide bushing 9 against the pressure of the spring 10 in equilibrium. The slide bushing 9 covers with its piston parts normally, the channels 11 and 12 so that no oil may penetrate from the external oil conductor 13 into these canals. The oil conductor 13 is fed by the main constant pressure control oil pump 26 of the turbine set which, at the same time is used for the supply of the power means for the movement of the steam admission valve.

If, for example, the rotational speed of the shaft 1 increases on unloading of the turbine, the oil pressure in space 8 increases and displaces the bushing 9 against the spring 10 until a new equilibrium condition is attained between the oil pressure and the spring force. At the same time the pressure oil is released from the

conductor 13 by the entrance of liquid or oil into the canal 11 and the oil may penetrate from there through the hole 14 into the space above the piston 16. At the same time, the slider bushing 9 opens the exit of the oil from the underside of the piston 16 over the canals 15 and 12 into the open. The auxiliary piston 16 moves downward and takes with it the pulling stick 17 and with it the wedge or cam 18. This wedge at the same time displaces the system spring plate 19, spring 10 and bushing 9 opposite to the introduced regulating movement until the canals 11 and 12 are again covered by the bushing 9, and on the occurrence of this, the regulating process is brought to rest. The steam admission to the turbine (not shown) is varied by this regulating process through the levers 20 and 21 and the control slider 22, the spring 27 operating a rigid member (this only holds for the opening process), because its spring tension is larger than the small resistance in the stick. In the above-described process, the downward movement of the pulling stick 17 effects an upward movement of the control slider 22 since the lever 21 at first has its pivot point on the valve spindle 25 as pivot. As the slider 22 is moved upwardly, pressure oil enters from the conductor 13 in the upper side of the force piston 24 and simultaneously the oil from the under side of the force piston flows away, so that the steam valve 23 of the turbine closes. The valve comes to rest when the spindle 25 is led through the lever 26 of the control slider 22 again to the center position.

On a decrease of the turbine rotational speed by reason of the loading, the above-described regulating process takes place in the reverse sense. The degree of nonuniformity of the regulator is determined by the selection of the hubs and lever lengths, as well as by the inclination of the wedge 18. The construction and the operation of the regulator in accordance with this description is known.

To limit the maximum permissible moment at any instant, a piston 31 serves which adjusts a stop 32 that cooperates with the lever system 23, 21 in such manner that the opening of the steam admission valve 23 for the turbine is limited by the stop 32. The piston 31 is controlled by the control slider 33 which is set through the levers 34, 35 by a regulating instrument 36 recording the maximum permissible torque. The regulating instrument has two wattmeter systems 37 and 38 operating opposite to each other which act on a common shaft 39. The system 37 measures the rotational moment transferred from the generator 40 to the motor 41. This device has a field coil 42 which is connected to a current transformer 43 and is excited in proportion with the stator current. The deflecting coil 44 is connected through the choke 45 to the potential transformer 46. The potential transferred by the potential transformer is displaced in phase by 90° with reference to the operating current portion of the current. Since the choke coil, if it is very large in comparison to the ohmic impedance of the measuring mechanism, effects a displacement of the current flowing therethrough of 90°, the current flowing in the frame is in phase with the work current portion of the machine stator current. The measuring mechanism 37 accordingly produces a torque on shaft 39 proportional to

$$\frac{E I \cos \theta}{f}$$

which is proportionately equal to the transmitted torque.

The maximum permissible torque is dependent on the exciting current of the machines operating on each other. This value is measured by the wattmeter system 38, the field winding 57 of which is supplied with current proportional to the generator exciting current and the deflecting coil 58 of which is supplied with current proportional to the motor exciting current. Accordingly, by this system a torque is produced on shaft 39 proportional to the product of the generator and motor exciting currents. By comparing the torques opposite to each other of the two wattmeter systems 38 and 37 with the aid of the common shaft 39, the resulting torque which is present is measured so that, accordingly, the stop 32 may, at any time, be so set that the maximum permissible rotational movement is never exceeded.

The electrical regulating instrument which indicates the deviation from the maximum permissible torque may also be permitted to act on the control device in another manner. In Fig. 2, an exemplary embodiment is illustrated in which the instrument 36 influences the outflow cross-section 25 of the gear-wheel and pump 3. The shaft 39 of the instrument in this arrangement displaces a slider 51 which acts to choke off the flow of the control oil into the open. For this purpose the control slider which sets the slot 6 in dependence upon the curve disk 47 of the rotational speed displacement is here arranged in a chamber 52 to which an oil conductor 53 leading into the open is connected. On the attainment of the maximum permissible rotational moment, the oil conductor 53 is choked off by the slider 51 so that in this manner an effect on the control of the steam admission in the sense of a limitation is attained. In the embodiment illustrated in Fig. 2, the separate stop 32 illustrated in the Fig. 1 apparatus and the associated control apparatus 31, 33 may be omitted.

The regulating instrument which measures the permissible maximum rotational moment may also be permitted to act on the lever which serves for setting the curved disk 47 and an exemplary embodiment of this is schematically indicated in Fig. 3. Here only the slider 48 of the gear wheel pump 3 is illustrated of the device for the control of the driving means supplied to the turbine. The curved disk 47 is displaced with the aid of the levers 61, 62, 63, 64, 65, 66. Here 64 identifies a control lever which is displaced in correspondence with the desired governor adjustment that is the desired turbine rotational speed, for example, by hand in the direction of the arrow upwardly or downwardly. On this displacement, the lever 63 rotates about the pivot point 67 fixed by the piston 68 and correspondingly displaces the curved disk 47. The instrument 36 which measures the maximum permissible rotational speed engages at the right hand end of the lever 66 and displaces this lever upwardly or downwardly in accordance with the measured value, the lever 66 also then turning about the point 67. In this displacement of the lever 66, the control slider 69 is displaced in such a sense that the piston 68 is lifted or dropped. The consequence of this is that the pivot point 67 of the stick is thrust upwardly or downwardly. On the attainment of the maximum permissible rotational moment, this pivot point is so set that the curved disk 47 is displaced in the sense of a decrease of the rotational speed to the value of the permissible turbine rotational moment.

Obviously, the given limiting device is not lim-

ited to the case treated in the example of a Thoma liquid regulator shown, but may of course be used also in other regulator devices, for example, spring regulators.

I am, of course, aware that others, particularly after having had the benefit of the teaching of my invention, may devise still other systems of control falling within the spirit of my invention. I, therefore, wish to be limited only by the scope of the claims hereto appended and such prior art as may be pertinent.

I claim as my invention:

1. In a ship propulsion system, in combination, a generator, a motor, a turbine for driving the generator, and means, responsive to the ratio of the maximum permissible motor torque to the transmitted torque adapted to control the steam admission to the turbine.

2. In a turbo-electric ship propulsion system, in combination, a turbine, a generator, having field windings, driven by the turbine; a motor, having field windings, coupled to the propeller to drive the propeller and connected to the generator to be supplied with electric energy; and means, responsive to the excitation currents in the field windings of both generator and motor and responsive to the power transmitted from the generator to the motor, adapted to control the fluid admission to the turbine.

3. In a power system the combination of, a prime mover, means for controlling the speed and thus the torque of the prime mover, a generator coupled to the prime mover, a motor connected to the generator, and means, responsive to the ratio of the maximum permissible torque of the motor and the torque transmitted, adapted to control the means for controlling the speed of the prime mover.

4. In a power system the combination of, a prime mover, means for altering the speed of the prime mover, a generator coupled to the prime mover to be driven by the prime mover, a motor electrically connected to the generator, and means, responsive to the ratio of the power transmitted from the generator to the motor to the product of the frequency of the generator and the field currents of the motor and generator, adapted to modify the operation of the means for altering the speed of the prime mover.

5. In an electric power system, including a generator, a variable speed prime mover for operating the generator, a motor connected to the generator, of means, jointly responsive to voltage of the generator, the armature circuit of the motor, the field currents of the motor and generator, the speed of the generator and the power factor, adapted to alter the operating characteristic of the prime mover.

6. In a power system including a variable speed prime mover, a generator driven by the prime mover, a motor electrically connected to be operated by the generator, means for controlling the speed of the prime mover, and means, jointly responsive to the torque transmitted by the motor and the maximum permissible torque, adapted to alter the operating effect of the means for controlling the speed of the prime mover.

7. In a power system including a variable speed prime mover, a generator driven by the prime mover, a motor electrically connected to be operated by the generator, and means responsive to a predetermined change in the difference between the pull-out torque of the motor and the actual torque transmitted by the motor adapted to alter the speed of the prime mover.

8. In a turbo-electric ship propulsion system, in combination, a turbine, a governor for the turbine adapted to maintain the turbine speed constant, governor adjusting means adapted to select the speed at which the turbine is to operate, a generator driven by the turbine, a motor connected to the generator adapted to drive the ship propeller, means responsive to the pull-out torque of the motor, means responsive to the torque transmitted by the motor, and means responsive to the differential effect of said last two means adapted to change the adjustment of the governor adjusting means.

9. In a turbo-electric ship propulsion system, in combination, a turbine, a governor for the turbine adapted to maintain the turbine speed constant, governor adjusting means adapted to select the speed at which the turbine is to operate, a generator driven by the turbine, a motor connected to the generator adapted to drive the ship propeller, means responsive to the pull-out torque of the motor, means responsive to the torque transmitted by the motor, and means responsive to the differential effect of said last two means adapted to jointly with said governor control the speed of the turbine.

10. In a turbo-electric ship propulsion system, in combination, a turbine, a governor for the turbine adapted to maintain the turbine speed constant, governor adjusting means adapted to select the speed at which the turbine is to operate, means for varying the turbine speed in spite of the governor operation, a generator driven by the

turbine, a motor connected to the generator adapted to drive the ship propeller, means responsive to the pull-out torque of the motor, means responsive to the torque transmitted by the motor, and means responsive to the differential effect of said last two means adapted to operate said speed varying means.

11. In a turbo-electric ship propulsion system, in combination, a turbine, a governor for the turbine adapted to maintain the turbine speed constant, governor adjusting means adapted to select the speed at which the turbine is to operate, means for varying the turbine speed in spite of the governor operation, a generator driven by the turbine, a motor connected to the generator adapted to drive the ship propeller, means responsive to the pull-out torque of the motor, means responsive to the torque transmitted by the motor and means responsive to the differential effect of said last two means adapted to control the operation of the speed varying means whereby the governor and speed varying means jointly alter the speed of the turbine.

12. In a ship propulsion system, in combination, an engine, means for varying the speed of the engine, a generator coupled to the engine, a motor coupled to the propeller, means responsive to the torque transmitted by the motor, means responsive to the pull-out torque of the motor, and means responsive to the differential effect of said last two means adapted to vary the speed of said engine.

THEODOR DEEG.
